UNITED STATES PATENT OFFICE.

WILLIAM H. DAVIS, OF MUNCIE, INDIANA.

LAMPBLACK-MACHINE.

1,160,862.

Specification of Letters Patent. Patented Nov. 16, 1915.

Application filed April 27, 1914. Serial No. 834,878.

To all whom it may concern:

Be it known that I, WILLIAM H. DAVIS, a citizen of the United States, and a resident of Muncie, county of Delaware, and State of Indiana, have invented a certain new and useful Lampblack-Machine; and I do hereby declare that the following is a full, clear, and exact description thereof, reference being had to the accompanying drawings, in which like numerals refer to like parts.

The object of this invention is to save lamp black, which has heretofore been permitted to escape in the smoke passing upward from the devices employed for collecting lamp black.

The chief feature of the invention consists in mounting above and near the lamp black collecting devices a plate or ceiling, which is perforated with a number of holes to permit the escape of the smoke and not destroy too much of the draft, but which will furnish an extensive surface on which lamp black will be deposited. The lamp black deposited on such plate will be of a very fine quality, as it has been so fine as not to become deposited on the depositing devices below. Also, means is provided for collecting or scraping the lamp black from this plate or ceiling preferably so as to keep it separate from the remainder of the lamp black because of its better quality.

The nature of the invention will be understood from the accompanying drawings and the following description and claim.

In the drawings, Figure 1 is a vertical transverse section through lamp black apparatus. Fig. 2 is a section on the line 2-2 of Fig. 1, through a part thereof. Fig. 3 is a plan view of a portion of a perforated ceiling or plate.

There is shown in detail a building having walls 10 and a roof 11, with lamp black collecting devices 12 mounted therein on members 13 and over burners 14, from which the smoke issues against the underside of the devices 12, whereby said devices 12 may collect the lamp black.

The invention is not limited to any particular lamp black collecting devices, as there is a variety of them, but it is understood by all skilled in the art that these devices 12 collect only a portion of the lamp black from the smoke or fumes, and chiefly, the coarser portion. The finer particles escape with the smoke and pass upward.

The object of this invention is to catch as much as possible of these lamp black particles escaping in the smoke.

Immediately over the lamp black collecting devices a plate 15 is mounted in the nature of a ceiling and having through it a number of perforations 16. This plate is flat and horizontal, preferably, and it collects on its underside a considerable portion of the lamp black particles which pass upwardly of the smoke from the devices 12, and yet, said plate 15 does not entirely obstruct the escape of the smoke, as it may pass through the perforations 16.

The lamp black, which collects on the underside of the plate 15, may be scraped off or removed by a scraper 20 mounted in an open-top box 21 carried by sprocket chains 22 on sprocket wheels 23 and shafts 24 driven by a belt 25 from any suitable source of power. The box 21 is elongated like a trough, and at the end of its movement it passes between the sprocket wheels 23 and turns over, so as to dump its contents in any suitable receptacle, not shown.

The invention is not limited to the particular means for scraping the plate 15, nor to the particular form of said plate, provided it is perforated to permit the escape of the gases and yet the major portion of the plate is left to collect the lamp black.

The invention claimed is:

The combination with a lamp black collecting device, of a flat horizontal perforated plate mounted above the same in a position to collect lamp black from the smoke passing upward from said collecting device, and a continuously moving scraper extending transversely of said plate and mounted in an open-top box for collecting said lamp black, said box being carried by an endless chain so that the scraper is operative only when moving in one direction and adapted to expose every part of said plate to the flame for the same length of time before being scraped.

In witness whereof, I have hereunto affixed my signature in the presence of the witnesses herein named.

WILLIAM H. DAVIS.
